(57) **CLAIM**

The ornamental design for a washing machine, as shown and described.

DESCRIPTION

FIG. 1 is the front perspective view of a washing machine showing our new design;
FIG. 2 is a front elevation view thereof;
FIG. 3 is a rear elevation view thereof;
FIG. 4 is a side elevation view thereof;
FIG. 5 is another side elevation view thereof;
FIG. 6 is a top plan view thereof;
FIG. 7 is a bottom plan view thereof;
FIG. 8 is the front perspective view thereof, showing the washing machine in another configuration;
FIG. 9 is the front perspective view thereof, showing the washing machine in another configuration; and,
FIG. 10 is the front perspective view thereof, showing the washing machine in another configuration.
The broken lines are for environmental purposes only and form no part of the claimed design.

1 Claim, 10 Drawing Sheets
